Primary Examiner—Prabhakar Deshmukh

(74) Attorney, Agent, or Firm—Volpe and Koenig, P.C.

(57) **CLAIM**

The ornamental design for a lock, as shown and described.

DESCRIPTION

FIG. 1 is a perspective view of a lock according to my new design;

FIG. 2 is a second perspective view of the lock of FIG. 1;

FIG. 3 is a top plan view of the lock of FIG. 1;

FIG. 4 is a front elevational view of the lock of FIG. 1;

FIG. 5 is a bottom plan view of the lock of FIG. 1;

FIG. 6 is a rear elevational view of the lock of FIG. 1;

FIG. 7 is a left side elevational view of the lock of FIG. 1; and,

FIG. 8 is a right side elevational view of the lock of FIG. 1. The dashed lines in FIGS. 1-8 represent environment and are for illustrative purposes only and do not constitute part of the claimed design.
